MATERIAL FEEDING APPARATUS

William Carl Stripe, Scarsdale, N. Y., assignor to
 Combustion Engineering Company, Inc., New
 York, N. Y.

Application June 27, 1940, Serial No. 342,659

4 Claims. (Cl. 221—130)

This invention relates to improvements in feeders for granular materials and particularly to feeders for use with materials which tend to pack.

Although capable of other applications, the invention will be described as embodied in a fuel feeder forming part of a furnace stoker. Some particles of coal are so small in size and sufficiently moist that they tend to pack on or adhere to surfaces of a feeding mechanism and thereby impair the continuity or predetermined rate of fuel feeding to the stoker. The type of feeder to which my invention is directed employs a rotating element for controlling the advance of material through a throat or passage. It is an object of the invention to provide a rotating feeder element which is so constructed and arranged as to dislodge any material that adheres to surfaces with which it comes into contact while advancing.

How the foregoing, together with other objects and advantages as may hereinafter appear or are incident to my invention are realized, is illustrated in preferred form in the accompanying drawings, wherein:

Figure 1 is a sectional elevation through part of a fuel stoker embodying the invention.

Figure 2 is an enlarged end view of the rotary feeder shown in Figure 1; and

Figure 3 is a sectional view through the rotating feeder element taken on line 3—3 of Fig. 2.

Fuel flows through a conduit or hopper 10 to a throat or passage 11 between a revolving feeder element designated as a whole by 12 and a coal plate 13 forming part of the feeder housing. The rotating element 12 comprises a shaft 14 having a plurality of independent members 15 placed side by side on the shaft and rotating therewith. The members 15 may have irregular peripheral surfaces for gripping the fuel such as teeth 16.

The feeder 12 in this instance is a part of a spreader stoker 20 and delivers the fuel to the distributor blades 21 which are revolved by any suitable means so that fuel dropping between the distributor blades, is propelled along the tray 22 and discharged through the opening 23 into the furnace. It will be seen that the rate at which the fuel is introduced into the furnace is dependent upon the rate at which the fuel is delivered to the revolving distributor blades 21 by the feeder 12. The rate of fuel flow past the feeder element to the stoker may be controlled by the speed with which the element is rotated or by the dimensions of the throat opposite the

feeder where the latter revolves at a constant speed, or by a combination of the two.

Shaft 14 preferably is made square in cross section and each member 15 has a central rectangular hole in its hub 17 which fits loosely over the shaft, at least one dimension A of the hole being substantially greater than the dimension B of the square shaft 14. Thus, due to the pull of gravity and the pressure of the passing fuel member 12 will move transversely of the shaft by the amount of the clearance C between the hub and shaft at each half revolution of the shaft. Adjacent members 15 on shaft 14 are so mounted that the clearance C between shaft 14 and hub 17 of one of them is at right angles to the clearance of the adjacent members. As shaft 14 rotates the adjacent members will then move radially in alternation at each quarter turn of the shaft by the amount of the clearance C between hub and shaft. Consequently, the peripheral surfaces of the members simultaneously move out of alignment with respect to one another and this relative movement of the adjacent members dislodges any coal tending to adhere to the surfaces of the rotating feeder element.

Preferably I reduce the thickness of the hub of a member 15 at the sides where the opening in member 15 is widest to narrow the bearing 18 on shaft 14 at these locations. I thereby lessen the tendency of fuel siftings to lodge between the shaft and the hub which would occur if the bearing were of considerable width, which might decrease or prevent the relative movement between members. I have maintained a full width of hub 17 along the other sides of the shaft openings in members 15 as in this instance it is immaterial whether movement with respect to shaft 14 occurs in that direction. These longer hub widths maintain all the wheels at right angles to the shaft since each alternate wheel has a long hub at right angles to adjacent wheels.

Inasmuch as the fuel does not remain adhered to my improved rotating feeder element, the flow of fuel is at a rate substantially proportional to the speed at which the feeder element rotates.

What I claim is:

1. In a material feeder of the type described; a feeding member comprising a horizontally disposed rotary shaft; a plurality of feeding wheels each formed with a slot for mounting it on said shaft that has a length substantially greater than the thickness of said shaft; means operatively connecting said wheels to said shaft for rotation therewith, the width of the slot in the wheel being 55 such as to provide a loose connection between the

shaft and each wheel for permitting gravitational movement of the wheel along the length of the slot while at the same time securing each wheel against rotational movement on said shaft, adjacent wheels being so mounted on said shaft that the length of the slot in one wheel is at an angle to the length of slots in wheels at the sides thereof so that certain wheels are displaced relatively to adjacent wheels at intervals during revolution of said shaft for repeatedly disrupting the peripheral alignment of said wheels.

2. In a material feeder of the type described; a feeding member comprising a horizontally disposed rotary shaft; a plurality of feeding wheels each formed with a slot for loosely mounting it on said shaft that has a length substantially greater than the thickness of said shaft and a width sufficiently greater than the thickness of said shaft for fitting it on said shaft so as to be loosely mounted thereon and yet rotatable thereby, adjacent wheels being so mounted on said shaft that the longer dimension of the slot in one wheel is at an angle to the longer dimension in the slots in wheels at the sides thereof, whereby all wheels move with respect to said shaft under the influence of gravity during rotation and certain wheels are displaced with respect to adjacent wheels on said shaft at intervals during rotation of the latter for repeatedly disrupting the peripheral alignment of said wheels.

3. In a feeder for delivering material through a passage, a rotating element for controlling the advance of said material, comprising a square shaft, members mounted side by side on

said shaft for rotation therewith having central hubs with rectangular holes therethrough which loosely fit over said shaft, one dimension of said holes being greater than the other dimension and such other dimension being at right angles to the greater dimension of the hole of the next adjacent member thereby causing transverse movement with respect to said shaft and the adjacent member, the hub of each member adjacent the greater dimension of said hole being of relatively narrower width along the shaft than the hub adjacent the smaller dimension; a conduit for the material in advance of said rotating element; means forming a passage for the material from the conduit adjacent said element and means for rotating said element.

4. In a feeder for delivering material through a passage, a rotating element for controlling the advance of said material comprising a square shaft, members mounted side by side on said shaft for rotation therewith having central hubs with rectangular holes therethrough which loosely fit over said shaft, one dimension of said holes being greater than the other dimension and such other dimension being at right angles to the greater dimension of the hole of the next adjacent member thereby causing transverse movement with respect to said shaft and the adjacent member, the hub of each member adjacent the greater dimension of said hole being of relatively narrower width along the shaft than the hub adjacent the smaller dimension.

WILLIAM CARL STRIPE.
